United States Patent Office

Des. 225,323
Patented Dec. 5, 1972

225,323

CEILING PANEL

Thomas R. Smith, 93 Hendricks Blvd.,
Eggertsville, N.Y. 14226

Filed Apr. 5, 1971, Ser. No. 25,754

Term of patent 14 years

Int. Cl. D25—01

U.S. Cl. D18—2

Fig. 1

Fig. 2

Fig. 3

Fig. 4

FIG. 1 is a plan view of a ceiling panel showing my new design;

FIG. 2 is an edge view of the ceiling panel of FIG. 1;

FIG. 3 is a plan view of a modified form of ceiling panel also embodying my new design; and

FIG. 4 is an edge view of the ceiling panel of FIG. 3.

I claim:

The ornamental design for a ceiling panel, substantially as shown and described.
